[57] CLAIM

The ornamental design for a wireless keyboard with click keys, as shown and described.

DESCRIPTION

FIG. 1 is a top plan of a wireless keyboard with click keys, incorporating the new design;

FIG. 2 is a bottom plan of the wireless keyboard of FIG. 1; FIG. 3 is a rear elevation of the wireless keyboard of FIG. 1;

FIG. 4 is a front view of the wireless keyboard of FIG. 1, the keyboard being raised at the front so that the top of the case is parallel to the line of sight;

FIG. 5 is a left side elevation of the wireless keyboard of FIG. 1; and,

FIG. 6 is a right side elevation of the wireless keyboard of FIG. 1.
